UNITED STATES PATENT OFFICE.

JOHN C. BLANTON AND DOUGLAS J. SEXTON, OF FREEMAN, WEST VIRGINIA.

MAIL-BAG-DELIVERING APPARATUS.

1,244,284.

Specification of Letters Patent. Patented Oct. 23, 1917.

Original application filed June 3, 1916, Serial No. 101,623. Divided and this application filed January 18, 1917. Serial No. 143,061.

To all whom it may concern:

Be it known that we, JOHN C. BLANTON and DOUGLAS J. SEXTON, both citizens of the United States, and residents of Freeman, in 5 the county of Mercer and State of West Virginia, have invented a new and Improved Mail-Bag Delivering Apparatus, of which the following is a full, clear, and exact description.

10 Our invention relates to means for transferring a mail bag from a moving car to a track stand or vice versa. The present invention is a division of an application filed by us June 3, 1916, Serial No. 101,623, and 15 relates more particularly to the track stand included in the delivering apparatus.

Reference is to be had to the accompanying drawings forming a part of this specification in which similar reference characters 20 indicate corresponding parts in all the views.

Figure 1 is a sectional plan view on the line 1—1, Fig. 2;

Fig. 2 is a front view of a mail bag delivering apparatus embodying our invention;

Fig. 3 is a fragmentary perspective view showing the means for retaining the mail bag on the stand ready for detachment by 30 the receiving means on the car;

Fig. 4 is a fragmentary perspective view showing the means for receiving and retaining a mail bag on the track stand.

The track stand is to be employed with 35 devices on the car 10, which may be of any approved construction having a door 11, which has mounted thereon a rock shaft 12 having bearings on the car across the doorway at the front by any suitable means, such 40 as brackets 13. As described in our previous application a mail bag supporting arm 15 is slidable transversely in the shaft 12 in addition to rocking in a vertical plane with said shaft, the arm having a handle 17 at its 45 inner end for manipulating the same. At the outer end of the arm 15 is a cross arm 20, here shown as having at one end a retaining hook 21. The opposite end of the cross arm is provided with a head designated 50 generally by the numeral 22 adapted to support a mail bag for delivering the same to a track stand. To hang the mail bag on the head 22, a ring 24 is provided having a snap-hook 25 adapted to engage a ring 26, held

by a strap 27 on the mail bag 29. The parts 55 referred to form no part of the present invention and need not be described further.

A stand 42 is erected alongside of the track and is provided with a lower arm 43 and an upper arm 44, projecting in reverse 60 directions from opposite sides of said stand. The arm 43 has a retaining hook 45 at the end and a cross arm 46 rearward of said hook, said cross arm being pivoted at the center as at 47 to turn in a horizontal plane. 65 Retractile springs 48 are secured each at one end to the opposite ends of the cross arm 46 and at their opposite ends, said springs are secured to a fixed pin 49 or the like on the main arm 43.

70 On the arm 44 is formed a head 22^a in all respects the same as the head 22, including a retainer 23^a, corresponding with the retainer fully described in our previous application whereby a mail bag may be suspended by the described elements 24, 25, 26, 75 from the head 22^a of the stand.

When the arm 15 is projected to receive a mail bag, the hook 21 of the cross arm 20 will readily pass into the suspending ring 24 80 on the arm 44 of the stand 42, and the engagement of said ring 24 with the arm 15 will release the said ring from the retaining device 23^a. Similarly, if a bag 29 be suspended from the cross arm 20 on the car, the 85 hook 45 of arm 43 on the stand 42, will pass into the suspending ring 24 until said ring strikes the cross arm 46 which will release the retaining device 23 and detach the suspended mail bag. Any unequal contact of 90 the ring 24 with the arm 46 will be taken care of by the springs 48.

Having thus described our invention, we claim as new, and desire to secure by Letters Patent:

95 In a mail bag-delivering apparatus, a stand adapted to be placed in fixed position along a railway track, and means on said stand to deliver and to receive a mail bag, said means including a lateral arm on the stand, a cross arm on the lateral arm, inward from the end thereof, and pivoted to turn, and spring means yieldingly engaging the said pivoted cross arm and tending to return the same after pivotal movement thereof.

JOHN C. BLANTON.
DOUGLAS J. SEXTON.
